Des. 236,565
Patented Sept. 2, 1975

236,565

WINE RACK

Donald M. Fuller, 3896 Rosecrans,
San Diego, Calif. 92110

Filed Dec. 12, 1973, Ser. No. 424,101

Term of patent 14 years

Int. Cl. D6—04

U.S. Cl. D6—28

Fig. 1

Fig. 2

Fig. 3

FIG. 1 is a perspective view of a wine rack, showing my new design.

FIG. 2 is a side elevational view as taken from the rear of FIG. 1.

FIG. 3 is a top plan view thereof.

The broken lines shown in FIG. 1 are for illustrative purposes only.

I claim:

The ornamental design for a wine rack, substantially as shown and described.
